UNITED STATES PATENT OFFICE.

ERNEST HEDENSKOOG, OF MUSKEGON, MICHIGAN, ASSIGNOR TO THE BRUNSWICK-BALKE-COLLENDER COMPANY, OF CHICAGO, ILLINOIS, A CORPORATION OF DELAWARE.

PIN-SETTING MACHINE.

Application filed August 9, 1920. Serial No. 402,366.

To all whom it may concern:

Be it known that I, ERNEST HEDENSKOOG, a citizen of the United States, residing in Muskegon, in the county of Muskegon and 5 State of Michigan, have invented a new and useful Improvement in Pin-Setting Machines, of which the following is a specification.

This invention relates in general in pin 10 setting machines for bowling alleys, i. e., machines adapted to place the pins in desired playing arrangement upon the bowling alley beds.

A principal object of my present invention is the provision of a machine of this character which will accurately place the pins upon the spots in playing position and this independently of the wear of the pins from continued service or otherwise. 15 The continued bowling of the balls against the pins and their continued banging about the pit and upon the alley frequently chip and otherwise wear the pins, and particularly their body parts, i. e., their parts of 20 largest diameter, and since these parts are desirably engaged to guide the pins into position in pin setting machines the provision of a machine for accurate placement in front-to-back alinement of pins more or 25 less worn presents a difficult problem. My invention contemplates in this regard the provision of a pin setting machine, the pin setting action of which will not be dependent upon or influenced by the shape of the 30 pins or the wear they have sustained.

Another important object of my invention is the provision of a pin setting machine, the parts of which will be so constructed and arranged as to provide considerable clearance about the pins when 35 placed in it so that adjustment of parts and provision of parts of minutely accurate dimension may be eliminated.

Another important object of the invention 40 is the provision of a machine having these and other advantages, the pin receiving portions of which will permit easy, rapid placement of the pins in the apparatus without more than casual attention to the 45 operation, so that the attention of the attendant may be directed almost entirely to the picking up of the pins from the alley bed and the pit. In this connection my invention contemplates a machine into which 50 an attendant, after relatively little experi-

ence, may deposit the pins without looking at the machine at all.

Another important object of the invention is the provision of a machine of the character described consisting of relatively 60 few parts, all of sturdy construction, and also having in it a minimum number of relatively movable members.

Another object of the invention is the provision of a machine which will gently 65 place the pins off the spots and thereafter move them onto the spots, whereby tendency to lose the spots is eliminated.

Numerous other objects and advantages of the invention will be apparent as it is 70 better understood from the following description, which taken in connection with the accompanying drawings discloses a preferred embodiment thereof.

Referring to the drawings,

Figure 1 is a side elevation of a pin spotting machine embodying my invention, the bed of the alley and the cross supporting shaft being shown in section;

Fig. 2 is a front elevation thereof;

Fig. 3 is an enlarged top plan view of the setting frame;

Figs. 4 and 5 are enlarged front to back sections through the setting frame and showing the action in setting the pins upon 85 the alley;

Fig. 6 is a section taken substantially on the line 6—6 of Fig. 3; and

Fig. 7 is a section taken on the line 7—7 of Fig. 3.

For the purpose of illustrating my present invention I have shown on the drawing so much of a bowling alley as is believed necessary to an understanding of the invention. This comprises the usual bed 11, gutters 12 and side walls or partitions 13. The usual pit is located at 14 rearwardly of the bed. Upon the side walls or partitions 13 I provide an upright stationary framework comprising vertical members or posts 15 fastened at 16 on the tops of the partitions and extending up to a head or frame top 17 from which depend socket members 18 receiving the upper ends of the posts. This head has a centrally disposed forwardly extending bracket arm 19.

The invention includes a vertically movable frame comprising a lower member 21 for supporting the pins in upright position, and a sliding or rolling upper member 22 110

for receiving the pins. The lower or supporting member 21 in the present instance consists of a metal sheet having its marginal edges upturned to form reinforcing flanges 23. This frame member is of general triangular form and is provided with ten apertures 24 arranged in the triangular relation of the spots of the alley bed. These apertures are materially larger than the greatest 10 diameter of the pins and are surrounded by downwardly extending marginal flanges 25. Behind each aperture is located a pad S of any suitable material adapted to prevent undue wearing of the pins as they are placed 15 in the apparatus.

Two bracket arms 27 extend up from the front corner of the frame and carry a pivot pin 28 at their upper end. The frame is sustained by three cables, one 29 located at 20 the front, and two 31 at the back. The cable 29 takes over a pulley 32 pivoted in bearings 33 depending from the bracket 19 and this cable is fast at its other end to a winding drum 34 fixed upon a cross shaft 35 25 rotatably held in bearings 36 depending from the frame top or head 17. The two cables 31 are fast at their lower ends at 37 to the sides of the frame 21 and take over sprockets 38 also fast on the shaft 35. These 30 cables 31 support a weight 39 which counter-balances the apparatus or rather its moving parts.

A winding drum 41 is also fixed on the shaft 35 and a control cable 42 is wound 35 about it and is provided with a hand grasp 43. The upper frame member 22 comprises also a metal sheet 44 of general triangular form and having its marginal edges turned up into reinforcing flanges 45. Beneath this 40 are provided four flanged wheels 46 and 47 pivoted in lugs 48 extending down from the upper member 22. Two of the wheels 46 are located at the rear corners of the frame and engage upon the upturned flanges 45. Beneath this 45 It is intended that this member 22 shall have a movement forwardly of the machine in the setting operation and to this end flanged portions of the lower frame member are formed into straight tracks 49 extending lengthwise of the alley. The other two wheels 47 are located beneath the front end of the upper member 22 and engage angle tracks 51 suitably arranged for the purpose (see Fig. 3).

55 The plate 44 is provided with apertures 52 arranged in accordance with the arrangement of the apertures 24 and in position over the pads S when the machine is in pin receiving or upper position. These apertures 60 are preferably of diameter materially greater than that of the greatest diameter of the pins. Combined pin receiving and guiding pockets, indicated generally by reference character 53, are arranged to extend 65 up from about the apertures 52. Each

70 pocket 53 is preferably made of sheet metal material having a flange 54 at its bottom adapted to be fast upon the upper surface of the plate 44 and having an upwardly extending cylindrical part 55. Above the 75 cylindrical part 55 each pocket 53 is inclined rearwardly and upwardly and flares outwardly. At the top the pocket is provided with a portion extending straight up as indicated at 56. Thus constructed the 80 pins may be thrown into the open mouths thus provided and by reason of the shape of each pocket 53 the pin is brought to a standing or upright position.

85 In this position contact is made with the 80 body of the pin at the rear side and the head of the pin at the forward side. If desired these parts may be arranged so that the pin leans a slight amount toward the rear of the machine.

90 When the apparatus is lowered to deposit the pins upon the alley the upper frame member moves down with the lower frame member until the parts approach the alley bed. Just above the alley bed the upper frame member is moved forwardly from the position shown in Fig. 4 to that shown in Fig. 5. In this movement the round surface of the pin body is engaged by the 95 round surface of larger diameter of the 95 pocket 53. By reason of these differences of diameter the pin is brought into accurate alignment with its position upon the alley bed and the forward movement of the upper frame 22 by a straight line movement of the 100 pin thus aligned brings it into accurate registration with the spot it is to occupy. There is preferably a two-point engagement with each pin, or rather the pockets 53 preferably engage two elements of the surfaces of 105 the pins and on their opposite sides and in planes extending longitudinally of the alley.

110 The forward movement of the upper frame member 22 is accomplished by a mechanism which will now be described. A bell crank 57 is pivoted upon the pin 28 and has a depending arm connected by a link 58 with a lug 59 fixed on the forward end of the frame member 22. The other arm of this bell crank is connected to a rod 61 which 115 extends through the forward end 62 of the bracket 19. Collars 63 and 64 are fast on the rod, one above and one beneath the bracket, and a spring 65 is mounted upon the rod and between the collar 64 and the bracket 19. 120 When the pins are in the frame and a setting is desired the attendant grasps the hand hold 43 and pulls downwardly. As the frame approaches the alley bed the downward movement of the rod 61 is restrained by engagement of the collar 63 of the bracket arm and through the cushioning spring 65. This results in forward movement of the upper frame part 22. In this movement the pins are slid off the pads S and drop the 125 130

short remaining distance to the alley and behind the spots, this distance being preferably merely an inch or two. The frame continues on down this remaining distance, the 5 upper member 21 continuing toward the front and sliding the pins accurately on to the spots. Thereafter the frame is returned by the counter-weight 39 and as it approaches upper or pin receiving position the collar 63 10 engages the bracket 19 and returns the lower frame member 22 to the normal pin receiving position shown in Fig. 4. A yielding stop mechanism is provided to bring the parts to upper normal position without un- 15 due jar and this same mechanism serves to provide an accurate guide for the frame in the pin setting operation.

It consists of two long downwardly extending guiding sleeves 66 rigid in sockets 20 68 in the head 17 and slidably embracing rods 69 extending through slots 71 in the frame part 22 and fixed at their lower ends in receiving sockets 73. Collars 74 are loose upon the rods 69 and rest upon cushioning 25 springs 75 located upon the rods and between the collars 74 and sockets 73. These collars 74 engage the lower ends of the sleeves 65 when the parts come to upper position.

It will be manifest that the apparatus includes relatively few parts and particularly few parts in moving contact with each other.

An attendant, by reason of the wide flaring mouths of the members 53 and the shape and arrangement of these mouths, may 35 quickly and easily position the pins without careful attention to the accuracy of their placement in the apparatus so that the charging of the pin setting machine may be greatly expedited since substantially the entire attention of the operator may be given to the picking up of the pins from the alley bed.

It is thought that the invention and many of its attendant advantages will be understood from the foregoing description, and it will be apparent that various changes may be made in the form, construction and arrangement of the parts without departing from the spirit and scope of the invention or 45 sacrificing all of its material advantages, the form hereinbefore described being merely a preferred embodiment thereof.

I claim:

1. In a pin setting machine for a bowling alley, a vertically movable frame comprising an upper member for receiving the pins in substantially upright position and a lower member for supporting the pins in said position in the upper member, said 55 lower member having openings for the pins and said upper member being movable relatively to the lower member, and means for operating the upper member to move the pins bodily into the openings in the lower member.

2. In a pin setting machine for a bowling alley, a vertically movable frame comprising an upper member for receiving the pins in substantially upright position and a lower member for supporting the pins in said position in the upper member, said lower member having openings for the pins and said upper member being movable conjointly with and relatively to the lower member, and means for operating the upper member in or 70 about the lowered position of the frame to move the pins bodily on the lower member into the openings therein.

3. In a pin setting machine for a bowling alley, a movable frame for receiving a set 80 of pins and for setting them upon the spots of the alley bed, said frame comprising means for supporting the pins in upright position therein, and means for bodily moving said set of pins on said supporting 85 means and into registration with the spots.

4. In a pin setting machine for a bowling alley, a movable frame for receiving a set of pins and for setting them upon the spots of an alley bed, said frame comprising a plurality of pockets and means for supporting the pins in said pockets, and means for moving said pockets relatively to said supporting means to move the set of pins bodily on the supporting means and into registration with 95 the spots.

5. In a pin setting machine for a bowling alley, a movable frame for receiving a set of bowling pins and comprising a member having pockets to receive the pins, and a 100 member for supporting the pins in upright position in said pockets, and means for moving said pocket member relatively to said supporting member when the frame has been lowered into position resting upon or closely 105 adjacent to the alley bed for moving the set of pins bodily on the supporting member and upon said spots.

6. In a pin setting machine for a bowling alley, a movable frame for receiving a set of 110 pins and for setting them upon the spots of the alley bed, said frame comprising means for supporting the pins in upright position and means for engaging the pins in a plane extending lengthwise of the alley, 115 and means for operating the engaging means to move the pins bodily on said supporting means and into position upon said spots.

7. In a pin setting machine for a bowling alley, a movable frame for receiving a set 120 of pins and for setting them upon the spots of the alley bed, said frame comprising a relatively movable means for engaging the pins in a plane extending lengthwise of the alley, and means for operating the engaging means to move the pins bodily on said supporting means into position upon said spots.

8. In a pin setting machine for a bowling alley, a movable frame for receiving a set 130

- of pins for setting them upon the spots of
5 an alley bed, said frame comprising means
for supporting the pins in upright position
and means for engaging each pin at the
front and at the back thereof and in a plane
extending lengthwise of the alley, and means
for operating the engaging means to move
the pins bodily on said supporting means
and into position upon said spots.
- 10 9. In a pin setting machine for a bowling
alley, a movable frame comprising an upper
member having pockets to receive the pins,
said pockets being constructed to engage the
pins at the front and at the back thereof in
15 planes extending lengthwise of the alley, and
a lower member for supporting the pins in
the upper member, said upper member being
movable relatively to the lower member, and
means for operating the upper member to
20 move the pins bodily on the lower member
and into position upon said spots.
10. In a pin setting machine for a bowling
alley, a movable frame comprising an upper
member for receiving the pins in upright po-
25 sition and a lower member for supporting
the pins in the upper member, said lower
member having openings for the pins and
said upper member being movable relatively
30 to the lower member and in a plane substan-
tially parallel with the lower member, and
means for operating the upper member to
move the pins bodily on the lower member
and into the openings therein.
11. In a pin setting machine for a bowling
35 alley, a movable frame comprising an upper
member for receiving the pins in upright po-
sition and a lower member for supporting the
pins in the upper member, said lower mem-
ber having openings for the pins and said
40 upper member being movable relatively to
the lower member and in a plane substan-
tially parallel with the alley bed, and means
for operating the upper member to move the
pins bodily on the lower member and into
45 the openings therein.
12. In a pin setting machine for a bowling
alley, a movable frame comprising means for
supporting the pins in upright position,
means for lowering the frame to set the pins
50 on the alley bed, and means for bodily mov-
ing the set of pins at or about the completion
of said lowering movement to slide the pins
bodily and lengthwise of the alley bed on
and off of said supporting means, and onto
55 the spots on the alley bed.
13. In a pin setting machine for a bowling
alley, a movable frame comprising a mem-
ber for receiving the pins in upright position
and a member for supporting the pins in said
60 receiving member, said receiving member
having means for engaging each pin on op-
posite sides thereof at different heights and
in a plane extending longitudinally of the
alley, means for lowering and raising the
65 frame, and means for moving the receiving
- frame relatively to the supporting frame to
dislodge the pins from the supporting frame
and set them upon the alley bed.
14. In a pin setting machine for a bowling
alley, a movable frame comprising a member
70 having pockets therein to receive the pins in
upright position and a member registering
with said pockets to support the pins in the
pockets when the frame is in elevated po-
sition, said receiving member being movable
75 relatively to the supporting member and said
pockets having means for engaging the pins
at the front and at the back thereof in dif-
ferent planes and at different heights, means
for lowering and raising said frame, and
80 means for moving said receiving member rel-
atively to the supporting member and in a
plane substantially parallel with said sup-
porting member to dislodge the pins from
the supporting member and set them upon
85 the spots on the alley bed.
15. In a pin setting machine for a bowling
alley, a vertically movable receiving and set-
ting frame, comprising a pair of apertured
frame members, one located beneath the
90 other, and with the apertures out of regis-
tration when in upper position, whereby to per-
mit the pins to stand upright through one
frame member and upon the other said frame
member, said frame members having relative
95 horizontal movement when the frame is low-
ered to slide the pins into registration with
the apertures of the lower frame member to
deposit them upon the alley bed.
16. In a pin setting machine for a bowling
100 alley, a vertically movable receiving and set-
ting frame, comprising a pair of apertured
frame members, one located beneath the
other and with the apertures out of regis-
tration when in upper position, whereby to per-
mit the pins to stand upright through one
105 frame member, said frame members having
relative horizontal movement when the
frame is lowered to slide the pins into regis-
tration with the apertures of the lower frame
110 member to deposit them upon the alley bed,
and pin guides engaging the pins on front
and rear surface elements arranged in planes
extending lengthwise of the alley.
17. In a pin setting machine for a bowling
115 alley, a vertically movable apertured frame
upon which the pins may rest in upright
position, a pin positioning frame mounted
thereon and movable horizontally with re-
spect to the vertically movable frame in the
120 pin setting operation and engaging the side
of the pins in line contact and rearward in
the direction of the movement of the frame
to bring them into accurate registration with
the spots of the alley bed.
18. In a pin setting machine for a bowl-
ing alley, the combination of a pair of ver-
125 tically movable apertured frame members
and arrangeable at an upper pin receiving
position with the apertures of the one mem-

- ber out of registration with the apertures of the other to permit pins placed in the frame to extend through the apertures of the one member and rest upon the body of the lower, 5 means for lowering said frames to pin setting position, the lowering movement being accompanied by relative horizontal movement of the frames to bring the apertures into registration to permit the pins to rest 10 upon the alley, and said movement continuing to slide the pins on the alley bed into accurate registration with the spots.
19. In a pin setting machine for a bowling alley, the combination of a pair of vertically movable apertured frame members and arrangeable at an upper pin receiving position with the apertures of the one member out of registration with the apertures of the other to permit pins placed in the 20 frame to extend through the apertures of the one member and rest upon the body of the lower, means for lowering said frames to pin setting position, the lowering movement being accompanied by relative horizontal movement of the frames lengthwise 25 of the alley to bring the apertures into registration to permit the pins to rest upon the alley and said movement continuing to slide the pins on the alley bed into accurate registration with the spots.
- 30 20. In a pin setting machine for a bowling alley, a frame movable toward and from
- the alley bed adapted to support the pins in the lowering movement in upright position and pin pockets having rearwardly flaring 35 mouths and curved surfaces for engaging respectively the body of the pin at the rear and the head of the pin at the front.
21. In a pin setting machine for a bowling alley, a frame movable toward and from 40 the alley bed adapted to support the pins in the lowering movement in upright position and pin pockets having rearwardly flaring 45 mouths and curved surfaces for engaging respectively the body of the pin at the rear and the head of the pin at the front, said curved surfaces being of larger radius than the pin parts engaged thereby.
22. In a pin setting machine for a bowling alley, a frame movable lengthwise of the 50 alley and for receiving the bowling pins and placing them upon the alley bed in upright position, said frame sliding the pins, after placing them upon the alley bed, into accurate registration with the spots. 55
23. In a pin setting machine for a bowling alley, a frame for receiving a set of pins and setting them upon the spots of the alley bed, said frame comprising fixed supports for the pin bottoms and a plurality of 60 pockets conjointly movable to slide the pin bottoms off the supports and along the alley onto the spots.

ERNEST HEDENSKOOG.
